(57) **CLAIM**

The ornamental design for a combined miniature basketball backboard and hoop, as shown and described.

DESCRIPTION

FIG. 1 shows a first embodiment of a combined miniature basketball backboard and hoop, showing my new design, wherein a shooting target is attached on the basketball backboard and a net is coupled with the hoop; and, FIG. 2 shows a second embodiment of a combined miniature basketball backboard and hoop, showing my new design, wherein a dart target is attached on the basketball backboard and a net is coupled with the hoop.
